UNITED STATES PATENT OFFICE.

RALPH G. AREY, OF WORCESTER, MASSACHUSETTS, ASSIGNOR TO WORCESTER BILT-RITE COMPANY, OF WORCESTER, MASSACHUSETTS, A CORPORATION OF MASSACHUSETTS.

WINDSHIELD CLEANER.

Application filed December 3, 1923. Serial No. 678,244.

My invention relates to cleaning devices for use in connection with windshields, so that rain, snow, and other similar matter can be wiped from the face of the windshield 5 and a clear space thus be provided, through which the driver of an automobile, or other vehicle, can readily see.

In my copending application, Serial No. 641,960, filed May 28, 1923, there is shown 10 and described an improved windshield cleaner, in which the wiping element is operated by an improved electro-magnetic device having all the capabilities of a small electric motor, without the complication and 15 high manufacturing cost of the latter.

My present invention contemplates a windshield cleaner in which the wiping element is actuated by an electro-magnetic device operating on the same magnetic principle as the device of the above mentioned copending application, but embodying radical improvements in mechanical arrangement and construction, whereby the device is rendered more effective and reliable in 20 operation, and is made capable of ready adjustment and control. The above and other advantageous features of my invention will hereinafter more fully appear, reference being had to the accompanying drawings in 25 which

Fig. 1 is a view of a portion of the rear face of a windshield, showing my improved cleaner mounted thereon.

Fig. 2 is a view in front elevation of my 35 improved cleaner with the front cover removed therefrom.

Fig. 3 is a view in end elevation of the cleaner shown in Fig. 2.

Fig. 4 is a transverse sectional view along 40 the line 4—4 of Fig. 2, looking in the direction of the arrows.

Fig. 5 is a longitudinal sectional view along the line 5—5 of Fig. 2.

Fig. 6 is a diagrammatic view, showing the 45 position of the armature when deenergized.

Fig. 7 is a diagrammatic view, similar to Fig. 6, showing the position of the armature when energized.

Fig. 8 is a fragmentary view, showing on 50 an enlarged scale, the details of the circuit controlling device shown in Figs. 2 and 5.

Like reference characters refer to like parts in the different figures.

Referring to Figs. 1 and 3, my device 55 generally consists of a rectangular casing 1

having a removable cover 2 which is here shown as being arcuate in form, although it is not necessarily so. As best shown in Fig. 4, the cover 2 is bent over along its edges, as indicated at 3, which bent over portions 60 coact with projections 4 provided on the casing 1 to maintain the cover 2 in position. The material of the cover 2 is preferably of a somewhat resilient nature, so that it is possible to flex the portions 3 past the 65 projections 4 when it is desired to remove the cover 2.

As best shown in Fig. 3, the back of the casing 1 is provided with a hollow boss 5 extending through an opening 6 provided in 70 a frame 7 of the windshield. The boss 5 is threaded, and a nut 8, coacting therewith, serves to clamp the cleaner to the windshield frame 7. The boss 5 is further provided with an opening 9, see Fig. 4, in which is 75 rotatably mounted a shaft 10 carrying at its end a wiping element, designated at 11 in Figs. 1 and 2. While any desired form of wiping element may be employed in connection with the shaft 10, I have illustrated 80 a particular form of wiping element and holder which is fully shown and described in my copending patent application, Serial No. 678,245 and filed December 3, 1923. For this reason, details of the wiping element 11 will not be further described 85 herein.

As best shown in Fig. 5, the shaft 10 extends through the casing 1 beyond the boss 5 and terminates in an offset or crank portion 12. The crank portion 12 is connected by means of a link 13 to a pin 14 provided on a spur gear 15 and eccentric with respect to the stud 16 on which the gear 15 is rotatably mounted. The gear 15 is in mesh 90 with a pinion 17 carried by a shaft 18 rotatable within a sleeve 19 carried by the casing 1. A worm gear 20 is carried at the other end of the shaft 18, and as clearly shown in Fig. 2, is in mesh with a worm 21 95 carried on the shaft 22 of my improved electro-magnetic device, which will now be described.

As best shown in Fig. 5, the armature shaft 22 is rotatably supported at its ends 105 in cylindrical bearings 23 and 24 which are preferably of the so-called "oilless" type, such as wood, or other fibrous material suitably impregnated with a lubricant. The right hand bearing 24 is enclosed in a metal- 110

lic sleeve 25 threaded in a bushing 26 carried by the end of the casing 1. The sleeve 25 is counterbored beyond the bearing 24, thus leaving an annular space surrounding the 5 shaft 22, in which is located a length 27 of flexible conducting material which is in contact with both the shaft 22 and the inner surface of the bushing 26. The function of the material 27 is to provide a continuous 10 electrical contact between the armature shaft 22 and the casing 1.

The shaft 22 carries a pair of spaced pole pieces 28 and 29, between which is carried a coil 30 surrounding an enlarged portion 22^a 15 of the shaft 22. As best shown in Fig. 4, the pole pieces 28 and 29 are of such length as to leave a narrow clearance space between their curved ends and the top and bottom portions of the casing 1 when the shaft 22 20 is turned. One terminal of the coil 30 is connected to the pole piece 28, while the other terminal thereof is connected to a contact plate 31 surrounding the shaft 22, and separated therefrom by suitable insulation 32.

25 From the foregoing, it is apparent that an electric current conducted to the plate 31 will traverse the winding 30, to energize the same, from whence it will pass through the shaft 22 to the casing 1, which is shown as 30 being grounded. As previously stated, it is one of the objects of my invention to provide an extremely effective device for controlling the energization of the armature coil, and this device will now be described in detail, 35 with reference to Figs. 6, 7 and 8.

As best shown in Fig. 8, a terminal stud 33 extends through one end of the casing 1 and is separated therefrom by insulation 34. The outer threaded end of the stud 33 carries 40 a thumb nut 35 for suitably securing an electrical conductor 36 thereto, while the inner end of the stud 33 carries, in electrical contact therewith, a disk 37. The disk 37 is of thin conducting material and is provided 45 with an opening 38 for receiving the bearing 23, with an ample clearance space therebetween. A second disk 39 is also carried by the stud 33, this latter disk 39 being separated from the stud 33 and the disk 37 by 50 insulation 40.

The disk 39 is of thin conducting material having a considerable amount of inherent resiliency, and the disk 39 is also provided with an opening 41 clearing the bearing 23. 55 The lower portions of the disks 37 and 39 carry opposed contact members 42 and 43, which are normally spaced apart so that even though the disk 37 is permanently charged, by reason of its connection to the stud 33, the 60 disk 39 remains uncharged until it is flexed enough to bring the contacts 42 and 43 into engagement, by mechanism which will now be described.

As clearly shown in Fig. 8, the disk 39 65 carries a shoe 44 opposite to the contact 43,

which shoe 44 is always in engagement with the contact plate 31 carried by the armature shaft 22. The plate 31 is provided at diametrically opposite points with projections 45, and as the shaft 22 is turned, these projections are adapted to engage the shoe 44 and flex the disk 39 in the direction of the disk 37 a sufficient amount to bring the contacts 42 and 43 into engagement, as indicated in dotted lines. The form of the projections 45 is such that the engagement between the contacts 42 and 43 continues through about one eighth of a revolution, the disk 39 returning to its original position as soon as its shoe 44 passes off of a projection 45. It is obvious then that the coil 30 will be energized twice for each complete revolution of the armature shaft 22, and the particular relation between the periods of energization and the angular position of the 85 armature projections 28 and 29 will now be pointed out.

As clearly shown in Fig. 6, a line A, A, passing between the projections 45 through the axis of the shaft 22, is angularly displaced with respect to a line B, B, also passing through the axis of the shaft 22 about which the armature pole pieces 28 and 29 are symmetrical. Assuming then that the shaft 22 is to be turned in the direction of the arrow, it is apparent that the contact making projections 45 have a slight lag behind the armature projections. In the position of parts shown in Figs. 2 and 4, the armature 90 pole pieces 28 and 29 are shown in such a position that the projections 45 are out of engagement with the shoe 44, and consequently the contacts 42 and 43 are out of engagement. The above described position of parts is the inoperative position of the device, in which the winding 30 is deenergized, the armature shaft 22 is stationary and the wiping element 11 in an extreme upper position. When it is desired to start the cleaner 95 in operation, it is only necessary to take hold of a knob 46 provided at one end of the shaft 22, and thereby turn the shaft 22 until one of the projections 45 engage the shoe 44. When this occurs, the disk 39 is flexed toward the disk 37, thereby bringing the contacts 42 and 43 into engagement, and the coil 30 is immediately energized.

As previously pointed out with respect to Fig. 6, the projections 45 have a small angular lag behind the pole pieces 28 and 29, so that when a projection 45 engages the shoe 44, indicated in dotted lines, the pole pieces 28 and 29 occupy a position in which their leading edges are close to the top and bottom portions of the casing 1, see Fig. 7. Consequently, when the coil 30 is energized, as above described, the magnetic lines of force tend to flow from the pole pieces 28 and 29 to the walls of the casing, thereby exerting a 110 torque on the armature which tends to turn 115

it in the direction of the arrow. As the armature turns in response to the torque thus developed, one projection 45 leaves the shoe 44, thus separating the contacts 42 and 43 and deenergizing the coil 30. As this occurs, the armature continues to turn in the same direction of rotation by reason of the initial impulse, and as the other projection 45 engages the shoe 44, the coil 30 is again energized and another impulse given to the armature. It is obvious that the armature shaft 22 will quickly come up to speed and continue to rotate by reason of the alternate energization and deenergization of the coil 30. The rotation of the armature shaft 22 will be converted into oscillatory movement of the shaft 10 through the gearing and crank connection previously described, it being obvious that the wiping element 11 will move through one complete oscillation for each complete revolution of the gear 15. When it is desired to stop the cleaner, it is only necessary to take hold of the knob 46 and bring the shaft 22 to rest by the application of a small amount of pressure. When the shaft is brought to rest with both projections 45 out of engagement with the shoe 44, it is obvious that the armature will remain in this position. If by any chance the shaft should be held by the knob 46 with one of the projections 45 in engagement with the shoe 44, then the armature will tend to turn as the pressure of the fingers is released, and will automatically move itself into a position in which the coil 30 is deenergized by the separation of the contacts 42 and 43. The pressure of the fingers will oppose turning beyond this point and the shaft 22 will remain at rest.

Referring again to Fig. 8, a screw 47 is provided for adjusting the distance between the contacts 42 and 43. The screw 47 is in threaded engagement with the end wall of the casing 1, with one end thereof abutting insulation 48 interposed between the disk 37 and the screw 47. By turning the screw 47 into the casing, the lower portion of the disk 37 can be flexed in the direction of the disk 39, thereby decreasing the distance between the contacts 42 and 43. In this way, the time interval during which the contacts 42 and 43 are held in engagement by a projection 45, can be varied for regulating the speed of the armature shaft.

It is obvious from a consideration of Figs. 7 and 8, that the closer the contacts 42 and 43 are to each other, the greater will be the period of time during which the coil 30 is energized for each engagement of the shoe 44 by a projection 45. It therefore follows that the torque developed and the speed of the shaft 22 will be greatest for the closest setting of the contacts 42 and 43. In order to decrease the speed of rotation, it is only necessary to turn the screw 47 out of the

casing, whereupon the disk 37 will return to its original position and the contacts will move farther apart. A lock nut 49 is provided to secure the screw 47 in position.

From the foregoing it is apparent that by my invention I have provided an improved windshield cleaner in which an oscillatory movement is imparted to the wiping element by means of an extremely simple and effective electro-magnetic device. My device requires no auxiliary switch, a turn of the shaft 22 being sufficient to start it. It is apparent that when once set in motion, the armature shaft 22 will be turned continuously so long as electric current is supplied through the terminal stud 33, the speed being readily adjustable by the screw 47 to meet different operating conditions. The current is intermittently supplied to the winding 30 with a substantial absence of destructive arcing at the points of make and break, owing to the fact that the contacts 42 and 43 are composed of non-arcing metal, such as platinum, or alloys having the same properties. The only sliding engagement between current carrying parts is continuous, so that there is no possibility of arcing occurring between the plate 31 and the shoe 44.

The reduction gearing between the armature shaft 22 and the wiping element shaft 10 is such as to result in a relatively slow movement of the wiping element 11, compared to the speed of the shaft 22. For a given setting of the contacts 42 and 43, the armature shaft 22 is adapted to make approximately 1200 revolutions per minute, while the element 11 makes but fifty complete oscillations during the same period of time. Consequently, the wiping element 11 can be brought to rest in any desired position by taking hold of the knob 46, for it is obvious that any slight turning of the shaft 22 while the knob is being held, will result in no appreciable movement of the element 11. In this respect, my cleaner differs radically from prior electric motor driven cleaners, controlled by a switch, for the reason that the ordinary electric motor shaft continues to turn through a number of revolutions after the current is turned off, thereby moving the wiping element.

I claim,

1. In a device of the class described, a rotatable armature having windings and polar extremities, a non polarized stationary yoke of magnetic material disposed around said armature, a cam member carried by said armature, a stationary contact member, a movable contact member, and a second cam member adapted to operate said movable contact member upon being engaged by said first cam member.

2. In a device of the class described, a rotatable armature having windings and polar

extremities, a non polarized stationary yoke of magnetic material disposed around said armature, a cam member carried by said armature, a stationary contact member, a movable contact member, a second cam member adapted to operate said movable contact member upon being engaged by said first cam member, and adjustable means for moving said stationary contact member toward

10 said movable contact member.

3. An electromagnetic motor for windshield cleaners, comprising a casing of magnetic material in the form of a hollow rectangular parallelepiped with one side missing, a shaft of magnetic material rotatably

mounted within said casing, with its axis parallel to the central longitudinal axis of said casing, but offset with respect thereto, a winding symmetrical about the axis of rotation of said shaft, a pair of transverse pieces 20 of bare magnetic material carried by said shaft at opposite ends of said winding, and means controlled by the rotation of said shaft to periodically cause a unidirectional current to flow through said winding, whereby a torque is applied to said shaft when said transverse pieces approach the parallel edges of said casing along the open side thereof. 25

RALPH G. AREY.
